UNITED STATES PATENT OFFICE.

ALBERT H. BOGART, OF NEW YORK, N. Y., ASSIGNOR TO TIFFANY & CO., OF SAME PLACE.

PLATE-PRINTING MACHINE.

SPECIFICATION forming part of Letters Patent No. 224,132, dated February 3, 1880.

Application filed November 11, 1879.

To all whom it may concern:

Be it known that I, ALBERT H. BOGART, of New York, in the county and State of New York, have invented a new and useful Improvement in Printing-Presses for Printing from Engraved Plates, of which the following is a specification.

This invention relates to an improved mechanism for moving the table holding the engraved plate.

a a are the standards composing the side frame of the press. *b* is the table on which is placed the mechanism for holding the engraved plate. *c* is the pressure-roller which gives pressure to the card-board or material placed on the engraved plate for the desired impression.

Previous to my invention the pressure-roller contained a lug, and in the revolution of such roller this lug came into contact with another lug placed on the side of the table, and thus the table was drawn underneath the roller. This imparted a vibratory or jarring motion to the table which frequently marred the impression. A slow movement of the table through the machine was necessary to avoid such vibratory or jarring motion. The employment of hand-power has therefore been heretofore universally used with this class of printing-presses.

To overcome this difficulty I place at one side of the table a lever, *d*, having an up-and-down motion by reason of its being hung at the rear of such side on the pivot *e*, its outer end being retained in a frame, *e'*. This lever is kept in its highest elevation by a strong gun-spring, *f*, placed underneath it, one end of such spring resting in the lower portion of the frame *e'*. This lever contains a groove, *g*, along its upper portion, so that the cam *h* on the side of the pressure-roller *c* may move during its revolution therein, and hence draw both table and lever along by frictional contact until the table reaches the position at which the impression is made by the surface of the roller *c*. Then the cam-roller *i*, projecting farther out than the cam *h*, presses on the top of the sides of this groove *g* and presses still farther down the lever *d*. This causes the lever to become locked underneath the shoulder of the latch or trigger *j*, placed in the side of the frame *e'*, and as the roller *c* moves away from over the engraved plate the side lever *d*, being freed from contact

with the cam, permits the table *b* to run back 55 into its original position, where it is ready to receive another card or other material onto the engraved plate.

The table is run back in the same manner as heretofore practiced—namely, by aid of the 60 gravity-weight and cord *k*.

A small notch is made on the under side of the lever at *l*, in order that the spring *m* on the side of the machine-frame may take into it as soon as the table has run back into position again, and thus arrest any tendency of the table to vibrate at the end of its movement.

After the table has returned to its original position the latch *j* is pulled by the hand in 70 a direction away from the table and against its retaining-spring *j'*, which operation will release the lever, the gun-spring throwing the lever in an upward direction, and at same time the spring *m* will release itself from the 75 notch *l*. This brings the lever in a position to be acted upon by the cam *h* of the pressure-roller *c* as soon as another card has been placed in position on the table.

Thus it is seen the table is pulled through 80 by frictional contact, and can therefore be run at a greater speed than when it is operated by the old mechanism of lugs, as described, there being no jarring or uneven movements consequent upon such increase of speed. The 85 running capacity of the press is so much increased that steam-power may be profitably employed with it.

I claim—

1. The combination of the table with the 90 lever arranged at the side of such table and the cam and cam-roller attached to the pressure-roller operating the lever and the said table, substantially as described.

2. The combination of the table with the 95 lever and the latch for locking and releasing said lever, arranged at side of the table, substantially as described.

3. The notched lever arranged at the side of the table, in combination with a spring attached to the frame of the press, so as to arrest the vibratory movement of the table, substantially as described.

ALBERT H. BOGART.
